CLAIM

The ornamental design for a jar, as shown and described.

DESCRIPTION

FIG. 1 is a perspective of a jar;
FIG. 2 is a front view of the jar in FIG. 1;
FIG. 3 is a back view of the jar in FIG. 1;
FIG. 4 is a right side view of the jar in FIG. 1;
FIG. 5 is a left side view of the jar in FIG. 1;
FIG. 6 is a top view of the jar in FIG. 1;
FIG. 7 is a bottom view of the jar in FIG. 1;
FIG. 8 is a perspective of a jar;
FIG. 9 is a front view of the jar in FIG. 8;
FIG. 10 is a back view of the jar in FIG. 8;
FIG. 11 is a right side view of the jar in FIG. 8;
FIG. 12 is a left side view of the jar in FIG. 8;
FIG. 13 is a top view of the jar in FIG. 8; and,
FIG. 14 is a bottom view of the jar in FIG. 8.

The figures illustrate a jar. The nature and environmental use of the claimed design is a jar for holding health or beauty products.

The broken lines in the drawings illustrate the portions of the jar that form no part of the claimed design.

1 Claim, 14 Drawing Sheets
